UNITED STATES PATENT OFFICE.

WILLIAM N. BLAKEMAN, JR., OF MOUNT VERNON, NEW YORK.

MINERAL OIL.

1,385,037.

Specification of Letters Patent. Patented July 19, 1921.

No Drawing.

Application filed February 9, 1921. Serial No. 443,673.

To all whom it may concern:

Be it known that I, WILLIAM N. BLAKEMAN, Jr., a citizen of the United States, and resident of the city of Mount Vernon, in the 5 county of Westchester and State of New York, have invented a new and useful Improvement in Mineral Oils, which invention is fully set forth in the following specification.

10 The invention relates to the mineral hydrocarbon oils, obtained chiefly from the Texas, Gulf, and California oil fields. The oils in this class, or group, of which the "Texas oils" are regarded as the type, are 15 known commercially as asphaltic base oils, and are recognized chemically as being largely composed of unsaturated hydrocarbons. In applications Nos. 174255 and 174256, filed June 12, 1917, I have described 20 and claimed the utilization of these oils in the formation of paint-vehicles and paint-compounds, and the object of the present invention is to treat these oils in such a manner that, when used in various combinations, 25 they will exhibit increased activity and produce more satisfactory results.

This I accomplish by subjecting the oil to a hydrogenating process, either with or without oxidation.

30 Either the crude oil, or any of its fractions, distillates, or residuals, may be used in carrying out my invention, and hence by the term "Texas oil", "hydrocarbon" or "mineral oil" as used in this specification 35 and in the claims, I intend to include the crude oil and also the fractions, distillates, and residuals. The specific oil which I have employed is that from the Sour Lake district, Texas, preferably the available dis- 40 tillates now on the market, varying from .92 to .94 sp. gr. The specific gravity of the crude oil varies from .90 to .92, and that of the residuals from .990 to 1.000.

In demonstration of my invention, I select 45 a distillate of a light straw color, and of .9340 sp. gr. and subject it to the action of hydrogen in the presence of catalysts, with heat, until it assumes the color of light vinegar, a gradual deepening of color with 50 increasing gravity, indicating a progressive hydrogenation.

The resulting hydrogenated product will be very much heavier and thicker than the untreated oil, and will be found to be an 55 affinitive component when combined with

other oils, and, as such, will unite with all the drying, semi-drying and non-drying animal and vegetable fatty oils, in all plastic compositions. By combining these hydrogenated hydrocarbons in varying proportions with other oils, either drying or non-drying, a drying oil may be formed which will constitute a new paint-vehicle particularly adapted for use with anhydrous pigments, which will exhibit improved spreading and drying properties and diffusion of opacity when ground therein, as is fully described in my applications above referred to.

The oils with which the hydrogenated hydrocarbon may be combined include, tung, 70 linseed, cottonseed, corn, sunflower seed, soy-bean, cocoanut, palm-kernel and the various marine animal oils.

As described in my application No. 443671 filed herewith, remarkable results are obtained when tung oil is employed in conjunction with the Texas oils, there being apparently some affinity between them, which results in a greatly increased activity on the part of the Texas oil when combined 75 with fatty oils, and this activity is still further increased when the Texas oil is hydrogenated, as herein described. The tung oil is preferably mixed with the hydrogenated Texas oil before the latter is combined with 80 other oils, and the percentage to be used will vary in practice. As little as 5% will show an indicated action, but 15% will be found to give satisfactory results in most 85 cases.

The proportion of the hydrogenated Texas oil to be mixed with fatty oils will depend upon the character of the fatty oil and the purpose for which the mixture is to be used. From 5 to 25 per cent. may be used 95 in the formation of paint-vehicles, as described in my application No. 174,255. It may also be used as a diluent in liquid drier compositions.

The Texas oil, in addition to being hydrogenated, may be oxidized by being heated on oxidizers, such as the higher oxids of manganese, preferably in the presence of an oxygen carrier, such as turpentine spirits, as described in my application No. 443672 filed herewith. This oxidation may be effected either before or after hydrogenation—preferably after—and the activity of the oil will be found to be greatly increased by the double treatment.

Having thus fully described my invention, I claim:—

1. A mineral oil, of the Texas oil type, hydrogenated.
- 5 2. A mineral oil, of the Texas oil type, hydrogenated and oxidized.
3. A mixture of mineral oil, of the Texas oil type, hydrogenated, and a fatty oil.
- 10 4. A mixture of a mineral oil, of the Texas oil type, hydrogenated and oxidized, and a fatty oil.
5. A mixture of a mineral oil, of the Texas oil type, hydrogenated, and tung oil.
- 15 6. A mixture of a mineral oil, of the Texas oil type, hydrogenated and oxidized, and tung oil.
7. A mixture of mineral oil, of the Texas oil type, hydrogenated; tung oil; and another fatty oil.
- 20 8. A mixture of a mineral oil, of the Texas

oil type, hydrogenated and oxidized; tung oil; and another fatty oil.

9. The process herein described, which consists in subjecting a mineral oil, of the Texas oil type, to the action of hydrogen, 25 in the presence of catalysts, with the aid of heat; and also subjecting it to the action of oxidizers with the aid of heat.

10. The process herein described, which consists in subjecting a mineral oil, of the Texas oil type, to the action of hydrogen, 30 in the presence of catalysts, with the aid of heat; and also subjecting it to the action of oxidizers, in the presence of an oxygen-carrier, with the aid of heat.

WM. N. BLAKEMAN, JR
